The ornamental design for a screw-on ant moat for a bird feeder, as shown and described.

DESCRIPTION

FIG. 1 is a front perspective view of a screw-on ant moat for a bird feeder embodying my new design.

FIG. 2 is a right side view thereof, the left side and back views being substantially the same.

FIG. 3. is a top view thereof.

FIG. 4. is a bottom view thereof; and,

FIG. 5 is a bottom perspective view thereof.

[The portion shown in broken lines in FIG. 4 is environment only, and forms no part of my claimed design.]

*The broken lines depict portions of the screw-on ant moat for a bird feeder in which the design is embodied that are not considered part of the claimed design.***1 Claim, 5 Drawing Sheets****Matter enclosed in heavy brackets [ ] appears in the original patent but forms no part of this reissue; matter printed in italics indicates the additions made by reissue.**AMENDED
